SEDIMENTATION APPARATUS

Charles Harold Scott, Westport, Conn., and John P. Kolb, Queens Village, N. Y., assignors to The Dorr Company, Inc., New York, N. Y., a corporation of Delaware

Application December 8, 1938, Serial No. 244,506

4 Claims. (Cl. 210—55)

The invention is in fields relating to thickeners, clarifiers or similar sedimentation apparatus embodying a cornered non-circular basin or tank and an associated sedimented impelling and transfer assemblage that is horizontally-turnable about a vertically-extending main axis and which comprehends (1) a main raking mechanism movable in closed circular paths over a circular section of the tank bottom and adapted for transferring sedimented material from diverse portions of the circular bottom section of the tank to a sediment-discharge means leading from a lower interior portion of the tank, and (2) a corner-exploring and cleaning mechanism disposed for successively entering or exploring each corner of the tank, adapted for engaging sedimented material at diverse portions of the successive corner sections for transferring the sedimented material engaged thereby to the central floor section from whence it is ultimately transferred to the sediment discharge by the functioning of the main raking mechanism. The invention hereof is particularly concerned with a novel form of corner-cleaning mechanism and with a novel manner of embodying the same in the sediment-raking assemblage of which it constitutes a part.

The main raking mechanism embodies one or more rake arms generally formed of metal such as steel, in the form of structural shapes and flat connecting plates, all of which are rigidly secured together as by riveting or welding. These arms carry or have embodied therein raking blade elements inclined with respect to the forward path or travel of the arm whereby sedimented material engaged thereby is impelled and progressively transferred to a sediment discharge generally located at or near the central portion of the circular floor section of the tank bottom. Of these main raking arms at least one, possibly more, is preferably constructed with sufficient rigidity and strength for affording support from the outer end thereof for the corner-cleaning mechanism referred to and such main arm may be termed a strong rigid main arm. This corner-cleaning mechanism is auxiliary to the main raking mechanism. The corner-cleaning mechanism is carried from a strong rigid arm or carrier and adapted to explore the tank corners. It comprehends the auxiliary raking element or blade that is bodily swingable from said rigid arm or carrier through the medium of pivoted horizontally-spaced links the inner ends of which are mounted on hinge members carried

5 at an outer end of a strong rake arm of the main raking mechanism. Because of the horizontal spacing arrangement and disposition of the link constructions, one of the links may be referred to as an outer forward link while the other may be referred to as an inner rear link. The corner-cleaning mechanism embodies the links just referred to and also the auxiliary sludge raking element, which is in effect a corner-cleaning or raking blade. The exploring mechanism also includes a yieldable forcing means adapted to press constantly, in a general more or less outward radial direction, the free ends of the swingable links and the associated corner-raking blade carried therefrom. The auxiliary or corner raking blade which is carried from the free ends of the swingable links is of substantial horizontal extent or length. It is held and positioned so that one end thereof is constantly outwardly disposed 10 from the main axis as compared to the other end which is disposed inwardly or nearer to the main axis about which the main raking mechanism turns. The length of this auxiliary raking blade or corner-exploring element is such that for all 15 positions thereof the innermost end reaches to and preferably extends somewhat over the peripheral portion of the circular area that is served by the main raking mechanism. The corner-exploring element as a whole may be 20 viewed as trailingly disposed with respect to that portion of the sediment-raking assemblage from which it is carried through the medium of the swingable links. In fact, the swingable links and particularly the free ends thereof also have what 25 may be viewed as trailing disposition with respect to the arm upon which they are mounted and with respect to which they swing as the arm moves in closed horizontal paths about said main axis.

30 The tank has a guiding or resisting member provided as by a stationary strip or track. This strip may be located so as to define the outer margin of a non-circular settling floor portion or other cornered area within the tank. This strip is embodied in the tank as a part stationary therewith and generally within the lower interior portion thereof, but it is not necessarily within the lower portion of the tank according to the broader aspect or phases of the invention. A 35 member of the corner-cleaning mechanism, generally the outer end of the corner-raking blade thereof, constantly engages this guiding strip as the corner-cleaning mechanism moves forwardly in closed paths within the tank whereby the corner-raking blade is alternately moved to and

40

45

50

55

from the outermost extended and the innermost retracted positions therefor incident to its alternately being forced outwardly by the yielding pressing means referred to, as such outward movement is permitted by the outwardly progressing section of the guiding strip and inwardly against the constant pressure of the yielding pressing means because of the cam guiding action of the stationary inwardly progressing section of the guiding strip.

The present invention, therefore, according to a broad aspect thereof revolves about the employing of a corner-exploring and cleaning mechanism having a corner-raking element of substantial horizontal extent or length that is swingably or positionably mounted from a main arm or carrier through the medium of horizontally-swingable horizontally-spaced links, the free or swinging ends of which are connected to horizontally-spaced sections or portions of the corner-exploring element and more particularly to horizontally-spaced sections or portions of the corner-exploring element that are inwardly spaced from the outer end of the corner-exploring element whereby the latter during any inward or outward movement thereof is under the guiding influence of the links.

The invention according to one aspect thereof involves the employing of a corner-cleaning mechanism having a corner-raking element pivotally mounted at or near the free ends of horizontally-spaced swingable links that are in turn pivotally mounted on hinge members carried at the free outer end of a main raking arm which is in turn provided with sediment-raking elements functionally disposed for operation over a circular section of the tank bottom incident to the forward movement of the raking arm in closed circular paths about a vertically-extending axis within the tank.

This invention may be still further described as residing in a corner-raking blade of substantial horizontal extent that is pivotally supported from the free rear ends of a pair of links or link constructions that are horizontally-spaced with respect to each other so as to provide an outwardly-disposed link and an inwardly-disposed link, the forward ends of which links are pivotally mounted on a movable carrier that is turnable about a vertical main axis within the tank. The links which are thus pivotally mounted on the movable carrier or outwardly-extending arm, are disposed so that the free ends thereof are rearmost whereby the links are trailingly disposed with respect to the outer end of the carrier or arm from which they are supported.

In the practical embodiment of a construction designed for realizing the aspects or features above referred to, there is employed a yieldable or constantly outwardly pressing means for continually forcing the corner-raking blade to the outermost position therefor and also a stationary guiding strip or track section functioning to determine the successive outermost positions of the exploring sediment-raking element and to provide cam-like guiding surface as to those sections required for forcing the corner-raking element toward retracted position therefor as is the case during certain portions of the forward movement of the corner-raking mechanism.

Heretofore means have been provided for the purpose of enabling rotary sludge or sediment-raking assemblage to operate within square tanks. Certain of said prior structures have been in successful operation for several years. However,

the main raking arms thereof have been relatively light and corner-cleaning elements and other operative parts have been embodied in the prior raking assemblages in such a manner that they have not proven to be sufficiently popular or of a character to be generally recommended and accepted by constructing engineers and plant operators.

An object of the present invention is to provide a cornered non-circular clarifier or settler having main rake arms of sufficient rigidity to afford the necessary or required support for extensible and retractable corner-exploring sludge-removing means and to improve the manner of mounting as well as the mode of operation thereof; also to equip the main rake arms with an extension arm operating solely and continuously at the trailing edge of the main rake arm in spaced relation thereto while having arcuate reciprocation substantially radially of the circular area served by the main rake arms, whereby the extensible and retractable rake arm is adapted to operate within the corners of the clarifier beyond said circular area for removing sediment or sludge from the corner areas into the circular area operated on by the main rake arms.

A further object of the invention is to allow the said corner-cleaning blade to have greater freedom of movement to enable it to operate more effectively within the corner areas of the clarifier in both its entering and departing movements.

With the above indicated and other objects in view, the invention consists in the construction and novel combination and arrangement of parts illustrated in the accompanying drawings and set forth in the claims hereto appended, it being understood that various changes in the form, proportion and minor details of construction within the scope of the claims may be resorted to without departing from the spirit of the invention or sacrificing any of the advantages thereof.

As illustrative of a manner in which the invention hereof may be structurally embodied in an apparatus or unit of the class referred to, reference is made to the accompanying drawings constituting a part of this specification.

In said drawings Fig. 1 is a plan view of one embodiment of this invention.

Fig. 2 is a partial sectional view taken as on the planes indicated by the broken lines 2-2 of Fig. 1.

Fig. 3 is a vertical view showing the tank or basin construction partially in sections and in this figure the horizontally-turnable raking assemblage occupies a position somewhat different from that shown in Fig. 1 wherein the rake arms of this Fig. 3 are in position practically at right angles to a side wall of the tank.

Fig. 4 is a plan view illustrative of a main rake arm and the corner-exploring mechanism carried by and from the outer end thereof. In this figure the raking blades have been omitted from the underside of the main arm.

Fig. 5 is a perspective view illustrating details of the corner-exploring mechanism and the mode by which the horizontally-swingable corner-exploring element is supported by and carried from the outer end of a main rake arm. In this figure certain longitudinal or relatively horizontal members of the main arm have been indicated by dash and dot lines and therein is illustrated by full lines a certain transverse frame construction which is rigidly connected to or which

constitutes a part of the outer end of the main rake arm.

Fig. 6 is a vertical view of weight and chain construction and certain associated details whereby these parts constitute a part of the yieldable pressing means that is provided for forcing a corner-exploring element into constant engagement with the stationary guiding track or strip.

Figs. 7 and 8 are longitudinal and transverse views of a track-engaging block employed at the outer or track-engaging end of the corner-exploring element, Fig. 8 being a view taken as on line 8-8 of Fig. 7 looking in the direction of the arrows.

Fig. 9 is a detailed vertical view partially in sections and illustrates the manner in which the corner-exploring element is connected by a pivot-providing means to the outer ends of horizontally-swingable links and so as to be supported therefrom.

The sedimentation unit shown in plan in Fig. 1, and of which a vertical view partly in section appears in Fig. 3, includes a cornered non-circular settling tank 11 and a horizontally-turnable sediment-raking assemblage 12. This assemblage embodies a main raking mechanism or rotary carrier 13 turnable in circular paths about a vertically-extending main axis and disposed for operating over an underlying circular floor section of the tank bottom; and an auxiliary or corner-exploring or cleaning mechanism 14 constructed and disposed for functioning within cornered sections and operating over underlying cornered floor sections outlying but contiguous the aforementioned circular floor section.

The settling tank 11 may be made of any suitable material; it is frequently made of concrete. It embodies a bottom 15 providing a cornered non-circular settling floor area, an upstanding hollow pier 16 centrally disposed with respect to the non-circular settling floor area and a cornered non-circular marginal wall 17. The tank also has sump 18 provided in the bottom thereof. The sump portion and the pipe 19 leading therefrom provide a sediment discharge leading from the lower interior portion of the tank. At the upper portion of the tank there is a marginal member 20 providing an overflow weir at 21 that determines the normal operative level of the liquid within the tank. Supernatant liquid within the tank overflows this weir as and when the height of the normal level is exceeded. The overflow liquid passes into an effluent launder 22 and therefrom through an opening or conduit 23 is leading from the tank. The member or members providing this weir and the overflow launder construction constitute effluent withdrawal means that determine the normal level of the liquid within the tank and whereby supernatant liquid passes as clarified effluent from the tank.

An influent pipe or conduit 24 which is either horizontal or approximately so leads inwardly below the floor of the tank to the hollow interior of the pier 16. The pier has orifice sections 25 providing discharge ports 26 leading from the hollow interior thereof by which ports incoming liquid is delivered into the upper central portion of the liquid-holding section within the tank. Such delivery of inflowing liquid is into a central stilling well or chamber 27 provided within the marginal limits of a baffle or intermediate wall portion 28.

The members constituting the sediment-rak-

ing assemblage 12 are mounted so as to derive suitable support for the assemblage from a stationary bearing means and so as to have movement in closed horizontal paths about a vertically-extending main axis. In the construction shown this sediment-raking assemblage 12 derives its support from a stationary bearing member 30 which is carried by and from the pier but this assemblage might be otherwise supported in order that it may have its horizontal turning movement in closed paths about a vertically-extending main axis. In the construction shown a stationary superstructure 31 is indicated which derives some of its support from the marginal portion of the tank and some from the stationary pier. This stationary structure 31 provides a walkway affording access to a stationary motor 32 and stationarily housed speed reducing and power transmission mechanism 33 that are provided for imparting horizontal turning movement to the members constituting the sediment-raking assemblage.

The sediment-raking assemblage 12 embodies a turnable bearing member 34 which derives its support from the stationary bearing member 30 on said pier or from any other suitable associated stationary bearing member. An arm-supporting cage or carrier 35 is secured to, depends from and turns with the turnable bearing member 34. From the lower end of the cage or carrier 35 there radially extend and are carried structural arms 36 that move in circular horizontal paths about the fixed axis about which the sediment-raking assemblage turns. These arms 36 embody vertically and horizontally-spaced longitudinal members such as 37, 38, 39 and 40 which are suitably connected by transverse ties or diagonal braces such as 41 to 48 inclusive and connecting plates such as 49, 50, 51 and 52 into a skeleton type of fabricated steel or other metallic construction whereby a relatively light, rigid and strong arm results.

The arms 36 have a dual purpose. In the construction shown there are embodied therein or secured thereto so as to depend therefrom sediment-engaging elements as 53, 54, 55, etc. in the form of raking blades having an inclination rearward and inwardly in respect to a forward path of travel of the arms, whereby these raking blades engage, impel and progressively transfer sedimented material from the underlying circular section of the floor bottom toward and into the sump of the sediment discharge. This skeleton form of travelling arms is also sufficiently rigid to support thereby and from the outer ends thereof the auxiliary or corner-exploring mechanism 14 heretofore referred to. In the construction shown the radial arms 36 are in fact cantilever arms horizontally-turnable by and extending from the carrying member 35 therefor. The cantilever arms 36 and the carrying member 35 just referred to may be collectively but broadly referred to as providing a horizontally-turnable carrier, or carriers, by and from which the exploring and raking mechanism, or mechanisms, is or are supported.

By reference to Figs. 1 and 2, it will be noted that the bottom of the tank has a corner non-circular settling floor area or section marginally defined by a cornered non-circular guiding section which in fact is provided by the guiding strip or marginal track 60, having four straight sections 61 and a corresponding number of interspersed corner fillet sections 62.

The corner-exploring or auxiliary raking

mechanism has a corner-cleaning member or corner-exploring member constituting a mechanical element 63 having a depending sediment-engaging blade or sludge-raking member or portion 64. The mechanical element or member 63 may be broadly viewed as a movable rake frame of substantial horizontal extent or length and the depending portion or member 64 may be viewed as a portion serving as a raking blade or as a portion to which a raking blade may be attached. The composite construction just described as comprehending the parts 63 and 64 may collectively be viewed and described as an auxiliary raking or corner-cleaning element of substantial horizontal extent or length. In the construction shown the outer end portion of the corner-cleaning element or blade 63 is constantly yieldably pressed in an outward direction so that the outer end portion thereof constantly engages and presses against the marginal track or guiding strip 60. This outward forcing is by a yieldable pressing mechanism 65 (see Figs. 4, 5 and 6), that includes a forcing-weight 66, a chain 67 passing over a guide pulley 68 and connected to the free or movable end 69 of swingable arm 70 on and rigidly connected to the pivoted end portion 71 of a horizontally-swingable link 72. There are two horizontally-swingable links 72 and 73 for each corner-exploring mechanism and the free rear ends 74 and 75 thereof have pivotal connections at 76 and 77 to horizontally-spaced sections of the corner-cleaning element 63. Each of these pivotal connections 76 and 77 is inwardly spaced a substantial but different distance from the extreme outer end of the bladed member 63. As previously indicated the links 72 and 73, and more particularly the free rear ends thereof, have trailing disposition with respect to the structural arm or carrier member 36 from which they are pivotally mounted since the free or rear ends of the links constantly trail or are disposed in the wake of said carrier member or arm as it moves forwardly along the closed horizontal circular path of travel therefor.

Two corner-exploring mechanisms are shown in Fig. 1. It would be feasible to employ only one such mechanism. Each of these mechanisms embodies a corner-exploring element or blade 63 just referred to. In the construction shown each corner-exploring element 63 derives swingable support from the horizontally-swingable hinged links 72 and 73 that are pivotally mounted on fixed hinge-providing members 80 and 81 that are secured to and carried at the rear or outer ends of the horizontally-turnable carriers or cantilever rake-carrying arms thereof. In Figs. 4 and 5 it will be seen that the hinge-providing members 80 and 81 are in fact upper and lower horizontals connected by horizontally-spaced verticals 82 and 83 and provide at 85 and 86 and 87 and 88 horizontally-spaced upper and lower hinge elements affording pintle axial portions at 91 and 92 whereby and from which the pintle or pivoted ends of the horizontally-swingable links 72 and 73 are carried. In other words, the pintle axes 91 and 92 of these links may be broadly viewed as horizontally-spaced one outwardly with respect to the other or as more specifically viewed as horizontally-spaced one outwardly and forwardly with respect to the other. These pintle axes are so arranged or disposed that the links have substantially horizontal swinging movement. The links, or swingable link constructions just referred to, have sufficient rigidity of construction to ensure that the outer ends thereof will 75

not bend or substantially deflect during the operative movement thereof. Between the outer ends 74 and 75 of these links and the corner-exploring element 63 there are provided pivotal connecting members 89 and 90 illustrated, for example, in Fig. 9. Each of these pivotal connecting members, 89 or 90, as the case may be, comprises a vertically-extending pivot pin 96 that is mounted in a bearing member 95 at the outer swinging ends of the swinging link to which it corresponds. Each pivot pin also extends through receiving portions provided therefor at 96 by a part of the corner-cleaning element 63.

From Figs. 5 and 9 it will be manifest that the pivotal construction just described provides a means whereby the rear outer end of each link is pivotally connected to the corner-cleaning element 63 and also whereby it can be supported as well as guided by the links as required during the in and out movement thereof.

One of the links 72 and 73 may herein be considered as a guide means horizontally spaced from the other link, and operatively connecting the rotary carrier 13 with the corner-exploring member or element 63. Both links, or otherwise expressed, one link and the guide means are co-active and effective to guide said exploring-element in a fully pre-determined horizontal bodily movement relative to the rotary carrier 13 in inward and outward directions with respect to the vertical main axis of rotation of the carrier 13. It will be understood that the term "bodily movement" signifies the movement of a body or element in which all points of the body move in non-pivotal fashion with respect to the reference system. Such a bodily movement, for instance, in a horizontal plane may represent and in the case of the movement of the present corner-exploring member, does represent the resultant of a bodily linear movement plus a pivotal movement. Such composite bodily movement may kinematically also be termed as compound bodily movement.

The outermost end of each corner-cleaning element 63 is provided with a lignum vitae slide block 97 which is secured to the outer end portion of the corner-cleaning element through the medium of bolts 98 and 99 as are shown in Figs. 7 and 8. A strip marked 100 shown in Figs. 5, 7 and 9 serves as a squeegee at the lower edge of the raking blade 64 and is of brass or any suitable material to serve this purpose.

In the construction shown a circular central portion of the floor of the tank bottom slants slightly downwardly and inwardly, all of the tank bottom or floor might be horizontal, and the main raking mechanism primarily functions to serve the circular central portion of the floor, namely, the section immediately underlying the area over which the main raking mechanism travels in closed circular paths about a main vertically-extending axis. As to the outlying corner floor sections that are contiguous the circular central sections that are served by the auxiliary corner-exploring and raking mechanism these are horizontal and of approximately triangular form as will be seen from an inspection of Fig. 2 in conjunction with Fig. 1. In Fig. 1 there are shown in plan four of these approximately triangular sections and they are within the confines noted by a portion of a straight line section 61, a curve fillet section 62, and a portion of another straight line section 61.

In the tank construction shown there is provided for each cornered portion of the marginal

wall a small downwardly and inwardly sloping fillet-like section 101, of which the slope is relatively steep, and which is provided for deflecting or directing sedimented material into the cornered triangular floor section to which the sloping fillet corresponds. These sloping fillets are provided so as to avoid retention of any substantial residual deposits in the extreme corner areas left outside of the settling area as marginally defined by the guiding strip or marginal track 60.

The hinge-providing members 80 and 81 have been embodied in a relatively strong but light end frame provided for and at the outer end of a rake-carrying arm or main raking member 13. This end frame includes the upper and lower hinge-providing members 80, 81, the horizontally-spaced vertical members 82 and 83 connecting the same, vertically-spaced horizontal members 102 and 103 to which the upper and lower ends of the vertical members 82 and 83 are connected and diagonals 104 connected to and connecting the vertical members 82 and 83 whereby the entire end frame is diagonally braced. The horizontals 102 and 103 are respectively connected to the longitudinals 37 and 39 and 38 and 40 of the rake-arm or main raking member 13. The end frame structure just described may be viewed as embodied in and constituting an outer end frame that imparts rigidity and strength to the box-like rake-arm structure that is formed of the aforementioned longitudinal members which are not only connected by the end frame just described but also by other transversely and diagonally-extending members into a strong formation which is relatively rigid throughout its length and which is well adapted to withstand any torsional strains about a substantially horizontally-extending line, to wit, torsional strains that might tend to be set up or created by the trailing auxiliary corner-raking mechanism incident to the functioning thereof. In this connection it will be noted that the corner-cleaning element 63 may be viewed as a swinging bodily-movable sludge-engaging member which has horizontal in and out bodily movement because of its being supported at the outer end of a swinging construction, or as otherwise expressed, because of its being supported in offset relationship from a pivotal support, or supports, located at its outer end of the main raking arm 13, namely, through the medium of a laterally-extending member or members, constituting or providing a horizontally-swingable carrying element therefor.

The operation of the device to which this invention relates is as follows:

Incoming liquid having matter therein to be settled therefrom is supplied through the influent pipe or horizontal feed conduit 24, passes upwardly through the rising leg or passageway provided by the hollow central pier 16 and ultimately passes as delivered influent through discharge openings 26 of the port-providing section 25 at the top of the pier. The thus delivered incoming liquid is stilled and dispersed or spread out within the initial receiving chamber 27 which is marginally-defined by the baffled or intermediate wall portion 28. The liquid passes from within this initial receiving chamber toward the marginal effluent launder 22 so that ultimately the clarified supernatant liquid overflows the weir 21 and passes into the launder and therefrom on its way from the sedimentation tank.

Settleable solids precipitate and collect as sediment at or over the entire area of the cornered

non-circular settling floor provided at the bottom of the tank.

The sediment-raking assemblage is supported from the stationary members providing a supporting bearing above the normal level of the tank, or as otherwise expressed, at an elevation higher than that of the weir 21. As already indicated, this raking assemblage extends downwardly into the liquid-holding section of the tank and includes the main and auxiliary raking mechanism which are conjointly employed for respectively raking the circular central section at the bottom of the tank and the outlying cornered sections that are contiguous and juxtaposed with respect to the central section just referred to. As already pointed out the raking assemblage is mounted and actuated so that it has forward turning movement in horizontal closed paths about a vertically-extending axis which is concentric with the hollow pier. The main raking mechanism has horizontal turning movement in circular paths so that the sediment-engaging elements or raking blades thereof travel over the underlying circular central floor section and the sediment-engaging elements or raking blades thereof function to impel and transfer sediment engaged thereby from diverse parts of the circular central floor section toward and into sediment discharge 18, from which it is ultimately passed from the bottom of the tank. During this horizontal turning movement of the main raking mechanism there is also a horizontal forward turning movement of the auxiliary or corner-raking mechanism in closed non-circular paths. The horizontal movement of this auxiliary mechanism in closed non-circular paths is under the progressive guiding and the constantly outwardly pressing influence of the stationary guiding track or strip 60 on the one hand and the yieldable but constantly outwardly pressing influence of the pressing weight mechanism 65 heretofore described. According to the combined operating influences just described the corner-cleaning element 63 of the auxiliary raking mechanism is constantly urged toward the outermost position therefor by the pressing weight 66 and the flexible connector which is connected to swingable-arm 70 that is integral with or connected to a part of the linkage mechanism or swingable element by which the corner-cleaning element or member 63 is swingably supported. In this way the forward or outer end of the bodily-movable corner-cleaning element 63 is constantly but yieldably outwardly pressed against the stationary guiding track or strip 60 and follows along a path defined by the track or strip. This corner-exploring element as has already been pointed out is provided with a slide block 97 which is preferably of lignum vitae whereby there is realized a type of sliding member which is well adapted to function in a liquid medium and to withstand wear during the constant pressing engagement which it has with the guiding track or strip 60 and which in the form shown is stationarily located at the bottom of the tank and is embodied in the structure constituting the tank. As the result of this engagement with the track and of the constant outward pressure embodied by the yieldable pressing means, it will be seen that the horizontally-swingable corner-cleaning element follows the track or guiding strip defining the outer margins of the non-circular cornered sections of the settling floor area and is well adapted to function within the outlying cornered section of the tank and

over the cornered floor portions thereof. Thus, as the sediment-raking mechanism turns it causes the corner-cleaning and sediment-transfer element 63 to traverse over the cornered floor section in a manner whereby sediment lodged therein is engaged and impelled and transferred from the successive outlying corner-floor sections into contiguous portions of the central circular floor area referred to, while at the same time the main raking mechanism functions to engage sediment passed to or on diverse parts of the in-lying central circular floor section or area and to transfer the sediment engaged thereby toward and ultimately to the sediment discharge sump 18.

In connection with each non-circularly raked cornered floor section it is to be noted that the sediment supporting area or sediment-receiving and supporting surface is preferably flat and horizontal or substantially so. As to the circularly-raked central section, this may be either flat and horizontal or dished according to the desires of an operator or designer.

That which is herein referred to as the forward end of a section of the track or guiding strip 60 is determined by that which is referred to as the forward raking movement of the sediment-raking assemblage. With respect to the track or strip 60 it will be noted that while it functions as a relatively continuous member, it is preferably made up of the four straight sections 61 and the four arcuate or fillet sections 62 assembled one after the other so as to provide a relatively continuous surface. As to these sections 61 and 62 the rear end of each is positioned in overlapping arrangement and radially outside of the forward end of the associated adjacent guiding section. This arrangement of the overlapping ends is clearly indicated in Fig. 1. In order to realize a preferred form the rear end of each track section is bent so as to extend outwardly and then rearwardly relative to the preceding main portion thereof, whereby a receiving-space is provided for the forward end of the contiguous or associated adjacent sections and whereby the guiding surfaces of the adjacent sections are arranged so as to provide a smooth continuity from one section to the other.

As to the end frame construction by which the horizontally-swingable links 72 and 73 are supported from the outer ends of the structural form of rake-carrying arms 36 of the main raking mechanism 13 it is feasible to mount that portion of the end frame which comprises the upper and lower horizontals 80 and 81, the horizontally-spaced verticals 82 and 83 and the crossing diagonals 102 so as to be adjustable in practically any direction with respect to the upper and lower horizontals 102 and 103 which are connected to or embodied in the structures constituting the rake-carrying arms 36.

This adjustment may be attained by the employment and provision of suitable adjusting and securing instrumentalities such as slotted portions provided in members, to wit, the vertical members 82 and 83 and the arm-carried horizontals 102 and 103, bolts employed for adjusting and securing purposes, to wit, such as pass through the slotted portions referred to whereby, for example, the verticals 82 and 83 can be vertically positioned with respect to and secured to the horizontals 102 and 103, and shims which, for example, may be employed for effecting certain desired vertical alignments by being placed between certain of the members such as, for example, between either or both of the vertical

members 82 and 83 on the one hand and either or both of the horizontal members 102 and 103 on the other hand.

By means such as those just referred to there may be readily realized the adjusting of the swingable links 72 and 73 to any desired elevation and there may be also attained an adjustment into the desired vertical position of the pintle axes about which the links have horizontal swinging movement and whereby said links will have proper operative movement therefor in substantially true horizontal paths. By such adjustment there is also realized the proper operative positioning and horizontal swinging movements of the corner-cleaning element or member 63 with respect to and over the relatively flat and horizontal floor surfaces of the outlying corner floor portions of the settling area of the tank bottom and above which the corner-cleaning element successively has operative sediment-raking and transferring movements as it travels in horizontal non-circular closed paths about the vertically-extending axis that is concentric with the upstanding pier 16.

In the construction shown there are two main rake-carrying arms that are substantially in diametrical alignment because of their extending in opposite radial directions from the horizontally-turnable cage or carrier 35 therefor. Also in the construction as shown there is a corner-exploring and raking mechanism 14 provided for and carried from the outer end of each rake-carrying arm 36.

It is feasible to employ a sediment-raking assemblage having diametrically-aligned rake-carrying arms, as the arms 36, but with only one corner-exploring and raking mechanism for the assemblage. In the instance just referred to the horizontally-swingable links of the corner-exploring and raking mechanism and the parts carried thereby may be supported from the outer end of only one of the rake-carrying arms. In such a construction it is advisable to provide counterweight means for the rake arm which does not carry or support the horizontally-swingable links. The counterweight required may be provided entirely, or in part, by a "dead" weight so to speak, secured, for example, to the outer end of the rake-carrying arm which does not support or carry the horizontally-swingable links, or this counterweight may be provided in part or wholly by extending the chain 67 past the center pier 16 whereby the sheave 68 and the forcing-weight 66 may be disposed on and carried by the rake-carrying arm which does not carry the horizontally-swingable links instead of on the rake-carrying arm which has at the free outer end thereof the horizontally-swingable links 72 and 73 and the parts carried thereby. In this way the forcing-weight 66 becomes a counterweight to balance in whole or in part the uneven loading on the sediment-raking assemblage and which would otherwise exist because of the horizontally-swingable links and the corner-cleaning element 63 supported therefrom being carried by only one of the arms.

In the event it becomes desirable to provide a construction or arrangement in which the weight 66 functions to cause the outer end of the corner-cleaning member to exert greater pressure against the guide track 60 during the periods of the outward or expanding movements thereof and so as to exert lesser pressure against the guide track during the periods of inward or retracting movements, this can be done by hav-

ing regard to the positioning of the arm 70 and its link 72 with respect to each other.

We claim:

1. A sedimentation unit comprising a settling tank, means for feeding liquid thereto, an effluent means determining the normal level of the liquid within the tank, a sediment discharge leading from the tank, means providing a cornered non-circular stationary guide track marginally defining a cornered floor area of the tank, a sediment-raking assemblage turnable in closed paths about a main vertically-extending axis and including a corner-exploring mechanism having a horizontally-movable corner-cleaning element of substantially horizontal extent for functioning over successive cornered floor sections, and yieldable pressing means for continuously forcing the corner-cleaning element toward the outermost permissible positions therefor as determined by said guide track with which it constantly engages; said corner-exploring mechanism being characterized in that it comprises a horizontally-turnable carrier provided thereupon with hinges having vertically-extending pintle axial portions that are horizontally-spaced with one pintle axis further outwardly disposed from the main axis than is the other pintle axis, horizontally-spaced swingable links trailingly disposed with respect to said carrier, of which the forward end of an outer link is swingably mounted on and carried from the pintle portion of an outer hinge and of which the forward end of an inner link is mounted on and carried by the pintle portion of an inner hinge, and pivot members for connecting the free trailing ends of said swingable links to horizontally-spaced sections of the horizontally-movable corner-cleaning element with sections horizontally-spaced from the outer end of said element whereby the latter is caused and permitted to have successive horizontal in and out swinging movement under the combined actuating and guiding influences of said yieldable pressing means and the non-circular stationary guide track as the corner-exploring mechanism turns about the main vertically-extending axis.

2. A sedimentation unit as defined in and by claim 1, according to which one pintle axis is both forwardly and outwardly disposed with respect to the other pintle axis whereby one of said horizontally-swingable links is outwardly

and forwardly disposed with respect to the other horizontally-swingable link.

3. A sedimentation unit as defined in and by claim 1, according to which the corner-cleaning element is pivotally connected to the free trailing ends of the horizontally-swingable links so as to be carried thereby and so as to depend therefrom.

4. In a sediment-conveying mechanism for collecting sediment over and from a settling area comprising corner settling portions and a central circular portion, a carrier rotatable about a vertical main axis and over said circular portion of said settling area, drive means for rotating the carrier, a sediment-conveying exploring device mounted upon said carrier and operable for collecting sediment from the corner portions of the settling area into the circular portion thereof, an exploring element, a link between 10 said exploring element and said carrier, means to pivotally mount one end of said link on said carrier for horizontal angular movement about a vertical axis, means to pivotally connect the exploring member with the other end of said link, to move horizontally about a vertical axis, means for movably connecting a portion of said 15 carrier, which portion is horizontally spaced from the point of pivotal mounting of said link on said carrier, with a portion of said exploring element, that is horizontally spaced from the point of pivotal connection of said link with the exploring element, said connecting means being effective to permit the exploring element to be moved bodily and pivotally in a horizontal plane, 20 said link and said connecting means being cooperative and effective to guide said exploring element in a horizontal bodily movement relative to the carrier in inward and outward directions with respect to the vertical main axis of the carrier, and control means cooperatively associated with said carrier and with said exploring element, said control means comprising a guide track extending along the outer margins of the settling area, and means mounted on the carrier 25 and connected to the exploring element for yieldingly pressing the outer end of said exploring element against said track as the carrier rotates.
